MIXING VALVE HANDLE

Tor Petterson, San Pedro, Calif., assignor to
Lloyd Spencer, Pasadena, Calif.

Filed May 8, 1970, Ser. No. 22,895

Term of patent 14 years

Int. Cl. D23—01

U.S. Cl. D23—29

FIG. 1 is a perspective view of the mixing valve handle, taken from above and from one side.

FIG. 2 is a perspective view thereof, taken from below and from one side.

FIG. 3 is a side view thereof.

FIG. 4 is a transverse sectional view thereof, taken through 4—4 of FIG. 3.

FIG. 5 is a bottom plan view thereof, taken on the plane of line 5—5 of FIG. 3.

I claim:

The ornamental design for a mixing valve handle, as shown.
